UNITED STATES PATENT OFFICE.

MOSES L. KLAUBER AND AUGUST W. MATZ, OF CHICAGO, ILLINOIS.

DESIGN FOR A GAME-BOARD.

SPECIFICATION forming part of Design No. 27,708, dated September 28, 1897.

Application filed March 15, 1897. Serial No. 627,704. Term of patent 7 years.

To all whom it may concern:

Be it known that we, MOSES L. KLAUBER and AUGUST W. MATZ, citizens of the United States, residing at Chicago, in the county of 5 Cook and State of Illinois, have invented a certain new and novel Design for a Game-Board; and we do hereby declare the following to be a full, clear, and exact description of the invention.

10 Our invention relates to a novel design for a game-board, the object being to provide a novel device of this character; and it consists in the features of the design hereinafter fully described and claimed.

15 The accompanying drawing illustrates our design for a game-board.

The board is provided with a diagram printed thereon consisting of five squares so placed as to form a cross, each of said squares 20 being provided with diameters and diagonals, at the intersection of which with the outer lines and corners thereof circular figures are represented. Some of said lines forming the outer edges and diameters of said squares are 25 represented as black, while the remaining lines are represented as white to indicate different colors.

The lowermost square, as shown in the drawing, forms what we term "the fort" in 30 the game as played, and in this figure a star is represented in each of the circles at the four corners and center thereof and in the circles midway between the corner-circles on

the outer sides of the square. The horizontal lines between the circles and said square 35 are represented as black, while the vertical and diagonal lines are represented as white.

The central square is provided in its center with an inner circle concentric with the outer circle and also with a similar figure on 40 its upper horizontal side at the intersection of the vertical diameter with said side. The remaining figures on the board consist of plain circles. The upper side of the uppermost square and the horizontal diameter and lower 45 side of said square are indicated by solid black lines, while the vertical sides, diameter, and diagonals are represented in white.

The two side squares have upper black lines, which form a continuation of the lower 50 side of the uppermost square and upper side of a central square and have also black horizontal diameters, while their lower sides, vertical sides, and diameter and their diagonals are represented in white lines. 55

We claim as our invention—

The design for a game-board, substantially as herein shown and described.

In testimony whereof we affix our signatures in presence of two witnesses.

MOSES L. KLAUBER.
AUGUST W. MATZ.
